UNITED STATES PATENT OFFICE.

CARL BERGMANN, JR., OF WEST HOBOKEN, NEW JERSEY, ASSIGNOR TO ECLIPSE MACHINE COMPANY, OF ELMIRA, NEW YORK, A CORPORATION OF NEW YORK.

ENGINE-STARTER.

1,330,282.

Specification of Letters Patent. Patented Feb. 10, 1920.

Application filed March 3, 1919. Serial No. 280,296.

To all whom it may concern:

Be it known that I, CARL BERGMANN, Jr., a citizen of the United States, residing at West Hoboken, in the county of Hudson 5 and State of New Jersey, have invented certain new and useful Improvements in Engine-Starters, of which the following is a specification.

My invention relates to a starter for an 10 engine, more particularly an internal combustion engine, and the object thereof is to provide a simple and efficient device of this nature and having the general characteristics of the starter shown in my Patent 15 No. 1,254,196, issued to me on January 22, 1918. My invention concerns more particularly the drive or transmission of an engine starting system and the embodiment thereof as herein shown is characterized by a rotatable shaft (either power or hand driven), provided with preferably a plurality of 20 coiled springs on which are mounted the driving member, (such as a pinion), adapted to automatically travel or advance in a direction longitudinally of the shaft to engage a rotatable engine member (such as the toothed fly-wheel), and to thereupon rotate with such shaft to rotate the fly-wheel and thereby start the engine. Besides being 25 the means whereby the driving member is so advanced into engagement with the engine member, the spring serves as a yielding driving connection in the starting of such engine member, and the subsequent 30 rotation thereof, and also as a cushioning means in case of abutting of the pinion teeth and fly-wheel teeth end to end.

In the drawing, Figure 1, is an elevation of a starter embodying my invention.

40 Fig. 2, an end elevation of the pinion.

Fig. 3, an elevation of a modified form illustrating the use of a plurality of springs.

Fig. 4, an end elevation of the pinion of such modified form of construction, and

45 Figs. 5, and 6, elevations of two other modified forms of construction.

Referring to the embodiment of my invention as shown in Fig. 1, (in which the starter is shown as power-operated by an 50 electric motor indicated at A, and in which the drive is shown as directly driven thereby), the extended armature shaft 1, carries a sleeve 2, secured thereto at one end by a pin 3, passing through the enlargement or 55 head 4, of the sleeve and through the shaft.

Upon this sleeve is mounted a coiled spring 5, with one end 5^a, fastened thereto, and its other end free and normally functionless. This spring, which encircles the sleeve and which is here shown extending nearly the 60 entire length of the sleeve in the space between the head and nut, acts as a thread for the driving member. The free end of the spring has a return bend forming a clutch jaw 5^b, for a purpose hereinafter explained. 65

The driving member is here in the form of a pinion 6, adapted, when advanced longitudinally along the shaft, to mesh with the teeth of an engine member which is here the fly-wheel 7. This pinion normally occupies a position intermediate the length of the spring, with the ends of the latter extending beyond both ends of such pinion, and is adapted to move to the left along the spring, whereupon, a clutch jaw 6^a, formed 70 on such pinion will be engaged by the jaw 5^b, of the spring.

Describing a cycle of operation, the armature shaft in its rotation rotates the sleeve and the spring, with the result that the pinion is automatically advanced to the left 80 into mesh with the fly-wheel. In this movement, the pinion clutch-jaw will be engaged by the spring clutch-jaw, whereupon, the spring will act as a torsion driving spring, 85 as the pinion now partakes of a rotary movement to rotate the fly-wheel. When the engine starts on its own power, the pinion is automatically demeshed and returned to normal position. 90

In the event of the abutting of the teeth of the fly-wheel, and pinion end to end, the shock of contact will be absorbed by the spring which will become compressed until the pinion is caused to rotate slightly to 95 bring the teeth into proper register for meshing.

In Fig. 3, I have shown a modified form in which a plurality (two) of springs 8, are employed and consequently a plurality of 100 spring clutches 8^a, and a plurality of clutches 9^a, on the pinion 9, (Fig. 4). This construction, with the clutches equidistantly placed, tends to keep the pinion centered on the sleeve, during the driving operation. 105

As may be desired, the spring may take all the torsion load of the pinion, as in the described constructions, or only the initial torsion load, in which case, means may be provided to take the final load. Such modi- 110

fied form is shown in Fig. 5, in which a positive jaw-clutch is provided between the pinion and rotatable shaft or sleeve. As there shown, the pinion 10, has a jaw 10^a, adapted to coöperate with a jaw 11, formed on or secured to said shaft. In the actual driving operation under full load, the pinion is thus in positive engagement with the shaft.

10 In Fig. 6, I have shown a simple form in which the spring 12, and pinion 13, have no clutching engagement, the free end of such spring terminating without any bend. In this construction, the spring has a compression action in the driving operation instead of a torsional action as in the other forms.

15 The spring may be of any desired shape in cross section, but I prefer to make it polygonal, such as the rectangular form shown. Obviously, the grooves in the bore of the pinion would be similarly shaped in cross section. The relative groove width and spring diameter are such as to permit 20 of the actions hereinbefore described.

25 The particular installation described is the inboard type of drive, with the pinion advancing inwardly toward the motor and without any outer bearing, but it is obvious 30 that the outboard type may be readily produced by locating the motor at the opposite end of the drive, than here shown, and providing a bearing at the outer end. Moreover, it is obvious that the rotatable shaft 35 instead of being a sleeve upon the extended armature shaft, may be one and the same, with such armature, or, in other words, the sleeve may be dispensed with, and the armature shaft utilized as the direct support for 40 the spring and pinion. In such case, the use of a smaller size of pinion is possible.

I claim:—

1. In an engine starter, the combination of a rotatable shaft, a coiled spring surrounding such shaft and secured thereto, and a driving member adapted to engage a member of the engine to be started but normally disengaged therefrom, said driving member having its bore screw-threaded and 45 directly threaded upon said spring.

2. In an engine starter, the combination with a rotatable member of the engine to be started, a rotatable shaft arranged parallel to the axis of said member, a coiled 55 spring surrounding such shaft and secured at its inner end thereto, the outer end thereof lying within the plane of said rotatable member, said driving member being threaded upon the spring and adapted to traverse 60 the same to the outer end thereof.

3. In an engine starter, the combination of a rotatable shaft, a coiled spring sur-

rounding such shaft and secured thereto, and a pinion whose bore is screw-threaded and directly threaded upon said spring. 65

4. In an engine starter, the combination of a rotatable shaft, a coiled spring surrounding such shaft and secured at one end thereto, the other end being normally free, and a driving member adapted to engage 70 a part of the engine to be started and threaded upon said spring, said member and free end of the spring being arranged to engage when such member is in engagement with the engine part. 75

5. In an engine starter, the combination of a rotatable shaft, a coiled spring surrounding such shaft and secured at one end thereto, the other end being normally free, and a driving member adapted to engage a 80 part of the engine to be started and threaded upon said spring, such member and spring having complementary clutch members adapted to engage when the driving member has engaged the engine part. 85

6. In an engine starter, the combination of a rotatable shaft, a coiled spring surrounding such shaft and secured at one end thereto, the other end being normally free, and a pinion adapted to mesh with a part 90 of the engine to be started and threaded upon said spring, such pinion having a clutch jaw and the spring having a complementary clutch jaw.

7. In an engine starter, the combination of a rotatable shaft, a coiled spring surrounding such shaft and secured at one end thereto, the other end being normally free, and a pinion adapted to mesh with a part of the engine to be started and threaded, 100 upon said spring, such pinion having on one end a clutch jaw and the free end of the spring having a return bend to form a complementary clutch jaw. 95

8. In an engine starter, the combination of a rotatable shaft, a plurality of coiled springs surrounding such shafts and secured thereto, at one of their ends, their other ends being normally free, and a driving member mounted upon such springs for 110 longitudinal movement therealong.

9. In an engine starter, the combination of a rotatable shaft, a plurality of coiled springs surrounding such shafts, and secured thereto at one of their ends, their other ends 115 being normally free, and a driving member mounted upon such springs for longitudinal movement therealong, the free ends of the springs and the driving member having complementary clutch members. 120

In testimony whereof, I have hereunto signed my name at New York, New York, this 13th day of February, 1919.

CARL BERGMANN, JR.
